US0D1046616S

(12) **United States Design Patent** (10) **Patent No.:** **US D1,046,616 S**
(45) **Date of Patent:** **** Oct. 15, 2024**

(54) **PACKAGING**

- (71) Applicant: **DENTSPLY IH AB**, Mölndal (SE)
- (72) Inventors: **Kerstin Paulsson**, Hovås (SE);
Christian Grönlund, Sävedalen (SE);
Sophia Wetterström, Hjälteby (SE);
Susanne Lindholm, Lindome (SE);
Anders Eliasson, Stockholm (SE);
Julian Stubbs, Stockholm (SE); **Robert England**, Stockholm (SE); **Cecilia Brandt**, Alingsås (SE); **Håkan Jansson**, Höör (SE)
- (73) Assignee: **DENTSPLY IH AB**, Mölndal (SE)
- (**) Term: **15 Years**
- (21) Appl. No.: **29/875,691**
- (22) Filed: **May 9, 2023**

Related U.S. Application Data

- (62) Division of application No. 29/744,349, filed on Jul. 28, 2020, now Pat. No. Des. 1,005,102.

CLAIM

The ornamental design for a packaging, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a packaging, showing our new design;

FIG. 2 is a front view thereof;

FIG. 3 is a bottom view thereof;

FIG. 4 is a left-side view thereof;

FIG. 5 is a rear view thereof;

FIG. 6 is a top view thereof; and,

FIG. 7 is a right-side view thereof.

1 Claim, 3 Drawing Sheets
(3 of 3 Drawing Sheet(s) Filed in Color)
